UNITED STATES PATENT OFFICE.

LEE O. CHURCH, OF VERNE, INDIANA.

DESIGN FOR A DRESSING-CASE.

SPECIFICATION forming part of Design No. 35,674, dated February 4, 1902.

Application filed January 3, 1902. Serial No. 88,364. Term of patent 7 years.

To all whom it may concern:

Be it known that I, LEE O. CHURCH, a citizen of the United States, residing at Verne, in the county of Knox and State of Indiana, have invented a new and original Design for a Dressing-Case, of which the following is a specification.

This invention relates to a new and original design for a dressing-case, and the essential features reside in the design as shown in the accompanying drawing, which illustrates a perspective view of the case.

The design is characterized by a lower horizontal body 1, with an upright frame 2 rising in a plane at a right angle to said body. The upper surface of the body is smooth, and from one side thereof projects an arm 3, with a circular terminal 4. The frame 2 has a central panel 5, embodying a reflecting-plate 6, and an

approximately triangular head 7, with a scalloped edge 8, curved shoulders 9, and scroll-lines 10. Extending outwardly from opposite sides of the head are upwardly curved or convex arms 11, having straight bars 12 connecting the outer terminals thereof and the base portions of the head, open spaces being formed between the arms and bars.

Having thus fully described the invention, what is claimed as new is—

The design for a dressing-case, as herein shown and described.

In testimony whereof I affix my signature in presence of two witnesses.

LEE O. CHURCH.
